DISTILLATION PROCESS

Filed Feb. 13, 1923

John V. E. Dickson, Inventor

By his Attorney, Chas. W. Mortimer.

UNITED STATES PATENT OFFICE

JOHN V. E. DICKSON, OF WOODCLIFF-ON-HUDSON, NEW JERSEY, ASSIGNOR TO THE
BARRETT COMPANY, A CORPORATION OF NEW JERSEY

DISTILLATION PROCESS

Application filed February 13, 1928. Serial No. 618,772.

This invention relates to the distillation of tar, such as coal tar, for example, that contains substances which easily undergo undesirable changes by the action of high temperatures. The invention is also applicable to so-called pitches or residues resulting from distilling off some of the volatile constituents from tar. Both the tar and the residue resulting from the partial distillation of tar which is to be treated by the process described in this application will be referred to as tar and it will be understood that the term "coal tar" as used in the claims herein is intended to include coal tar as well as coal tar pitch obtained from the partial distillation of coal tar.

It has been found that if coal tars are distilled in such a way that they are exposed to unusually high temperatures, during distillation, or are heated at the usual distillation temperatures for unusually long periods of time, the total oil recoverable as distillate from them is less than usual, and also the residual pitch is of higher melting point than usual, after a given percentage of oil has been removed as distillate.

The oils removed as distillate are almost always of higher commercial value than the residual pitches, and it is therefore desirable to carry out the distillation in such a way that either the maximum total yield of oil will be attained, or the highest possible percentage of oil will be removed before any given commercial grade of pitch has been formed.

The use of "tube stills", such for example as is disclosed on pages 485, 486, et seq. of the fifth edition, Part I, of "Coal Tar and Ammonia," by Geo. Lunge, Ph. D., published by The D. Van Nostrand Company, 1916, wherein the tar is heated as it passes continuously through a series of tubes, and is finally discharged into a chamber where the oil vapors and pitch residue separate, has been found to increase the total removable distillate, and also to give a pitch residue of lower melting point on the removal of a given percentage of distillate, as compared with the use of the ordinary discontinuous method of distillation, where a charge of tar is heated to boil-

ing and the various oils pass over successively, in vapor form to a condenser. Since approximately the same temperatures are attained in both processes, it is supposed that the difference in oil yields is due principally to the difference in the time during which the tar is heated, which is commonly about ten hours in the discontinuous method and less than one hour in the tube still. 55

Lowering the distillation temperatures, in the discontinuous method, by (a) carrying on the distillation under greatly reduced pressure (50 mm. of mercury, absolute pressure, or less), or (b) the rapid passage through the tar of a gas having no chemical action on it, has been found to produce results practically the same as those attained in the tube still. 60

Accordingly, it might well have been supposed that in any one of the three above methods (tube still, reduced pressure, or passage of gas) approximately the optimum conditions had been reached, with regard to the total oil yield attainable or the oil yield attainable in the manufacture of any given pitch. 70

However, I have discovered that, in a tube still, (a) by a sufficiently great further reduction of the time during which the tar is heated, greatly increased yields of distillate oil can be obtained, in the production of a given commercial grade of pitch; and (b) if, in addition to thus shortening the time, advantage be taken of the known boiling-point-lowering effect of reduced pressure (by artificially reducing the pressure in the separating chamber), a total yield of distillate can be obtained which is far in excess of that produced by any previously used means known to me. 80

For instance, a coke-oven tar of a type which usually gives a maximum oil yield of about 45% by weight in the commercial simple discontinuous method and about 65% by weight in the other improved methods mentioned above, has in the new method yielded as much as 80% by weight; and in making most commercial grades of pitch, as judged by their melting points, the difference in oil yield between the new method and the 100

other improved methods amounts to the equivalent of 35-15% of the tar used.

These results are accomplished by heating the tar as it passes through one or more tubular paths or zones, and discharging it at substantially its maximum temperature into a chamber or zone of relatively large volume and correspondingly low pressure compared with said heating zone; where the oil vapors separate from the residual pitch, the vapors passing on into a condensing system and the pitch flowing out continuously at the bottom of the separating chamber. It is important, however, that the time occupied by the tar in traversing the heated tubes should be very short. Since it would be very difficult to measure or to calculate the actual mean time taken by a particle of tar to traverse such an apparatus (because of the expansion due to rise of temperature, and the vaporization of oil taking place continuously during a considerable part of the travel), an indirect way of defining this length of time relatively must be used, and this will consist in defining the ratio of the cubic contents of the tubing traversed to the volume of the tar passing through it in unit time.

If the unit of volume be the cubic foot, and the unit of time be the minute, this ratio will indicate the mean time which would be occupied by a particle of tar in passing through such a piece of apparatus. This ratio for commercial tube stills is commonly about 60, but in the present invention it is not more than 10, and may be much less or in other words, the tar is passed through the heating tube or zone in amounts not less than one-tenth of the cubical capacity of said heating tube or zone per minute.

In order to reduce the ratio to such low values, particular attention must be paid to the manner of supplying heat. A low value of this ratio means that a comparatively large quantity of tar is being heated per minute in an apparatus of comparatively small volume capacity; and this necessitates an intense and concentrated application of heat. This invention is not limited to any particular method or means of supplying heat to the tubing through which the tar flows, but in the accompanying drawing is illustrated a form of apparatus, in which the heat may be supplied to the tubing by means of a bath of molten metal or alloy through which the tubing passes. The rapidity with which heat passes from a liquid to a metal in contact with it (as compared with the relatively slow passage of heat from a gas to a metal) permits a relatively large quantity of heat to pass per minute into the tube walls (and thence to the tar) without recourse to the very high temperatures in proximity to the tubes which would be necessary in order to transfer heat

at such a rate if the tubes were heated by direct contact with furnace gases.

In the accompanying drawing is illustrated diagrammatically an arrangement of apparatus by which the invention can be carried out. In the drawing, reference character 1 designates a tank for a supply of tar which may be pumped by means of the pump 2 through the tube 3 which is immersed in a bath of molten metal or hot liquid metal, such as mercury, lead, or other metal of low melting point, in the tank 4. The metal in this tank may be kept in the molten state by heating the same in any convenient way as, for example, by flames impinging upon the bottom of the tank 4 or by passing hot products of combustion through pipes passing through tank 4. A pipe 5 leads from the coil 3 to a separator 6 for pitch and vapor which is provided with a baffle plate 7. The pitch settles in the bottom of the separator 6 and passes through the pipe 8 into the pitch receiver 9, from which it may be withdrawn through the valve 10. The vaporized constituents pass from the separator 6 through the pipe 11 into the coil 12 in the condenser 13 where they are condensed and passed to the oil receiver 14 from whence the oil may be removed through the valve 15. The receiver 9 for the pitch and the receiver 14 for the oils are connected by pipes 16 and 17 to a vacuum producing means 18.

As the tar is fed into the coil 3, it passes upwardly and is heated by the heat transmitted from the molten metal while it is in transit through the coil 3. The amount of heat supplied will be sufficient to cause the desired amount of distillation to take place. The rate at which the tar is passed through coil 3 will be maintained as indicated above so as to produce an increased yield of oil or distillates in proportion to the amount of pitch or residue that is left.

The following are two examples out of many others that might be given to illustrate how the process has actually been carried out.

(1) A yield of distillate of 58% by weight with a pitch residue having a melting point of 237° F. has been produced at atmospheric pressure in the separating chamber, with a discharging temperature of about 810° F., and a rate of tar flow of about 70% of the cubic capacity of the heating tube, per minute.

(2) A yield of distillate of 75% by weight with a pitch residue having a melting point of 352° F. has been produced with a discharging temperature of about 740° F., and a rate of tar flow of about 38% of the cubic capacity of the heating tube per minute, the separating chamber being maintained at an absolute pressure of 55 mm. of mercury.

In both of the above examples, a coke oven tar was used, which by ordinary distillation 130

gives about 35% by weight of distillate in producing a pitch having a melting point of 237° F., and in an ordinary tube still or in the recirculated gas method gives about 46% in making a pitch of the same melting point.

5 It is not practical to make a pitch having a melting point of 352° F. by either the ordinary still or the ordinary tube still method because of danger of coking, but the 10 highest yields customarily obtained from such a tar by these methods are about 40% by the former and 58% by the latter in making a pitch of melting point about 300° F.

I claim:

15 1. The process of distilling coal tar which comprises passing said tar through a heated zone in amounts not less than one-tenth of the cubical capacity of said zone per minute, supplying heat to the tar while passing 20 through said zone at such a rate as to elevate it to a temperature sufficient to cause about 58% at least of the tar to volatilize at atmospheric pressure, and then discharging the tar thus heated into a zone of relatively 25 low pressure with respect to the pressure of said heated zone, thereby effecting a separation of the oil content in vapor form from the pitch content of the tar.

2. The process of distilling coal tar which 30 comprises passing said tar through a heated zone in amounts not less than one-tenth of the cubical capacity of said zone per minute, supplying heat to the tar while passing through said zone at such a rate as to elevate it to a temperature of about 740-810° 35 F. prior to its discharge therefrom, and then discharging the tar thus heated to a zone of relatively low pressure with respect to the pressure of said heated zone, thereby 40 effecting a separation of from about 58% to about 75% of the oil content in vapor form from the pitch content of the tar.

3. The process of distilling coal tar which 45 comprises passing said tar through a heated zone in amounts not less than one-tenth of the cubical capacity of said zone per minute, supplying heat to the tar while passing through said zone at such a rate as to elevate it to distillation temperature prior to 50 its discharge therefrom and then discharging the tar thus heated into a zone maintained at a pressure less than atmospheric, thereby effecting the separation of the oil content in vapor form from the pitch content 55 of the tar.

4. In a process of distilling coal tar to recover volatile oils therefrom and produce a pitch residue, wherein the tar is heated to distillation temperature while confined in 60 and flowing through a heated zone and vaporization of the volatile oils is thereafter effected by discharging the heated tar into a chamber of low pressure relative to that of said heated zone, the improvement which comprises passing said tar through said heated

zone at an increased rate of flow amounting to not less than one-tenth of the cubical capacity of said zone per minute, and supplying heat to the tar while passing through said zone at a rate sufficient to elevate it to distillation temperature prior to its discharge therefrom, whereby the time period to which the tar is subjected to heat in its passage through the zone is diminished thereby lowering the extent of thermal decomposition of the tar and increasing the oil yield, and recovering separately the volatile oil content of the tar liberated in the vaporization chamber and the residual pitch.

5. In a process of distilling coal tar to recover volatile oils therefrom and produce a pitch residue, wherein the tar is heated to distillation temperature while confined in and flowing through a tube and vaporization of the volatile oils is thereafter effected by discharging the heated tar into a chamber of low pressure relative to that of said heating tube, the improvement which comprises passing said tar through said tube at an increased rate of flow amounting to not less than one-tenth of the cubical capacity of said tube per minute, and supplying heat to the tar while passing through said tube by maintaining a body of molten metal in heat-exchange relation therewith at such a temperature as to elevate it to distillation temperature prior to its discharge therefrom, whereby the time period to which the tar is subjected to heat in its passage through the tube is diminished thereby lowering the extent of thermal decomposition of the tar and increasing the oil yield, and recovering separately the volatile oil content of the tar liberated in the vaporization chamber and the residual pitch.

6. In a process of distilling coal tar to recover volatile oils therefrom and produce a pitch residue, wherein the tar is heated to distillation temperature while confined in and flowing through a tube and vaporization of the volatile oils is thereafter effected by discharging the heated tar into a chamber of low pressure relative to that of said heating tube, the improvement which comprises passing said tar through said tube at an increased rate of flow amounting to not less than one-third of the cubical capacity of said tube per minute, and supplying heat to the tar while passing through said tube at a rate sufficient to elevate it to distillation temperature prior to its discharge therefrom, whereby the time period to which the tar is subjected to heat in its passage through the tube is diminished thereby lowering the extent of thermal decomposition of the tar and increasing the oil yield, and recovering separately the volatile oil content of the tar liberated in the vaporization chamber and the residual pitch.

7. In a process of distilling coal tar to

recover volatile oils therefrom and produce a pitch residue, wherein the tar is heated to distillation temperature while confined in and flowing through a tube and vaporization of the volatile oils is thereafter effected by discharging the heated tar into a chamber of low pressure relative to that of said heating tube, the improvement which comprises 5 passing said tar through said tube at an increased rate of flow amounting to approximately seven-tenths of the cubical capacity of said tube per minute, and supplying heat to the tar while passing through said tube at a rate sufficient to elevate it to distillation 10 temperature prior to its discharge therefrom, whereby the time period to which the tar is subjected to heat in its passage through the tube is diminished thereby lowering the extent of thermal decomposition of the tar 15 and increasing the oil yield, and recovering separately the volatile oil content of the tar liberated in the vaporization chamber and the residual pitch.

20 In testimony whereof I affix my signature.
